ELECTRICAL CONNECTER

Charles E. Gilbert, New York, N. Y.

Application October 11, 1935, Serial No. 44,514

6 Claims. (Cl. 173—361)

This invention relates specifically to electrical connectors of the unbreakable type in which the body is made of soft rubber or other similar elastic material.

5 Among its objects are the provision of a connector of this character in which the contact elements are seated securely and firmly and yet may be removed, if desired, without damage to the body; in which the seating and retaining 10 of the contact elements is positive and involves no distortion of the elastic body; to which the conductors may be connected if desired without soldering or twisting and yet are held securely and in which there are no bolts, rivets or other 15 similar anchoring devices. Furthermore, the connector of this invention may be connected to the conductor and assembled without the use of tools.

The form of connector shown herein for purposes of illustration and description is that of a 20 plug such as is commonly used for connecting appliances to electrical outlets. It will be understood, however, that the invention is not similarly limited but is capable of assuming many other forms.

25 In the drawing—

Figure 1 is a plan view of an electrical connector plug embodying the invention;

Fig. 2 is a longitudinal sectional view of the 30 same plug on the plane indicated by the line 2—2 of Fig. 1 viewed as indicated by the arrows; and

Fig. 3 is a view in perspective of one of the contact elements.

35 The plug selected for descriptive purposes herein consists of a body 1 molded of soft rubber, or other similar elastic material, and two contact elements 2 seated therein. The interior of the body 1 is hollow as shown at 3, and connects 40 with an opening 4 through which the electrical connector may be inserted. The body is also provided with two recesses 5 for the reception of the contact elements each of which opens into the interior 3 through an opening 6 intermediate its ends. The opposite or outer wall of each recess is also provided with a longitudinal channel 7 of sufficient width and depth to receive 45 an insulated wire.

The part of the body 8 between the recesses 50 for the contact elements is preferably conical in form, its apex 9 projecting into the interior in the direction of the opening 4. Each of the sides of conical section 8 is provided with a channel 10 of suitable dimensions to receive the 55 electrical conductor. The inner wall of each

recess 5 is also provided with a notch 11. The general cross-sectional dimensions of each recess 5 disregarding the channel 7 is the same as the similar dimensions of the contact element. That is to say, the dimensions are such that when the element is inserted it will make close contact with all four walls of the recess.

5 Each contact element, as shown in Fig. 3, consists of a strip of conducting material bent upon itself to form two legs 12 and 13, leg 12 10 being somewhat longer than leg 13. The end of leg 12 is provided with a notch 14 of suitable shape to tightly grip the wire passing therethrough. The end of short leg 13 is bent as shown, into a tongue 16 which, as shown in Fig. 15 2, rests against the side of the conical section 8 when the plug is assembled. Immediately above the end 16 of short leg 13 is an aperture 17 of sufficient size to permit the passage of an insulated wire and a similar aperture 18 in long leg 20 12 registers therewith. These apertures 25 register with channels 7 and 10 so that a continuous conduit for the conductor is provided from the interior 3 and around the end of the contact element to which it is attached.

To connect the conductor to this contact element the insulation is first stripped from the 30 end of the conductor to bare the wire within. The stripped end is then passed above tongue 16 through holes 17 and 18, down around the end 35 of leg 12 through the notch 14 and up the other side of leg 12 until its end may be pinched between the two legs of the contact element when they are pressed together.

The contact element with the conductor thus 35 connected to it may then be inserted in the plug body by passing it, bend first, through opening 4 into the hollow interior and then through the opening 6 into the recess 5 until tongue 16 strikes the surface of conical section 8 of the body. 40 Further pressure upon the contact element will cause the elastic body to give sufficiently to permit the end of leg 12 of the contact element to be inserted in the bottom of the recess 5. When the pressure is removed the body will return to 45 its original shape and the contact element will be held securely in place through its contact with the walls and the bottom of recess 5 and through the engagement of tongue 16 with conical section 8. Channel 10 in conical section 8 affords a 50 passage for the wire across the surface of tongue 16 to aperture 17 without impairing the engagement of tongue 16 with the surface of conical section 8. Similarly channel 7 permits the wire, 55 after it emerges from aperture 18, to pass down

- the outside of leg 12 of the contact element and through notch 14 without affecting the contact of leg 12 with the corresponding wall of the recess. Since short leg 13 does not project into the recess below opening 6 ample space is provided in that part of the recess for the upward passage of the wire along the inside of leg 12. The various bends assumed by the conductor and its passage through notch 14 which, as heretofore stated, is so shaped as to securely grip the insulation, together with the close engagement of the contact element with all four walls of the recess insure that the conductor will be held against any possibility of displacement.
- 15 If desired either or both of channels 7 and 10 in the body may be omitted and equivalent channels provided in leg 12 and tongue 16 of the contact element to secure the desired conduit for the conduction around the end of the contact element as described.

Although there is little likelihood of displacement of the contact element once it has been seated, as described it is conceivable that some extraordinary pull upon the conductor might accomplish this. Such displacement is rendered impossible, however, by providing one of the legs of the contact element (leg 13, for example) with a small tongue 19 which projects outwardly and towards tongue 16 and is positioned so as to engage notch 11 in the body when the contact is fully seated in recess 5. This tongue will effectively prevent accidental displacement of the contact element in the direction opposite to that from which it was inserted. Displacement in the other direction is, of course, impossible because of tongue 16.

In order to simplify insertion of the contact elements the body of the plug may be split, as shown at 20 in Fig. 2, from the end indicated by the opening 4 substantially to the apex 9 of conical section 8. This permits the sides of the plug to be sprung outwardly so that the interior is opened up and a much larger space obtained for manipulation of the contact elements during insertion. The elastic character and curvature of the sides will cause them to come together again and thereafter retain their normal shape just as though the split 20 had not been made. However, to insure against any possible separation during use the small end of the body may be surrounded by a metallic or other suitable removable ring 21.

It will be noted that when this connector is assembled no part of the body is distorted by the presence of the contact elements or the conductors. It will also be noted that the contact elements are locked against accidental displacement but that they can be removed, if desired, without damage to the plug body. It will also be noted that the assembly may be carried out with great ease and without the use of tools and that the entire connector may consist of only three elements, the body and the two contacts, each of one piece and involving a simple molding operation to form the body and an even simpler stamping operation to form each of the contact elements and that soldering of the conductor is not required to secure positive and permanent connection.

- 70 I claim:
1. An electrical connector comprising a unitary

elastic body having a hollow interior and two recesses, each terminating in a socket at its inner end and having an aperture immediately above said socket communicating with the interior of said body and a contact seated in each of said recesses and each consisting of a strip of conducting material folded upon itself so that one leg is longer than the other, the long leg being seated in said socket and the short leg passing through said aperture in said recess and engaging with an interior wall of said body, said interior wall of said body being provided with a channel connecting said interior with said recess, said recess also being provided with a channel extending from its bottom to a point opposite to that at which the other channel enters said recess and said contact element being provided with apertures affording communication from one channel to the other.

2. An electrical connector comprising a one-piece elastic body provided with a passage therethrough adapted to permit the introduction of an electrical conductor and a contact element through the same end, a socket in a wall of said body connecting with said passage and adapted to receive said contact element, a contact element which consists of a strip of resilient conducting material folded upon itself so as to form two legs in substantially parallel relation, the free ends of both of which pass through said passage, one of said ends being seated within said socket and the other of said ends being offset and engaging with the wall of said passage so as to maintain said other leg within said socket against longitudinal displacement.

3. An electrical connector according to claim 2 in which one of said legs is also provided with an offset tongue engageable with the exterior of said body as an additional means of maintaining one leg of said contact element within the socket against longitudinal displacement.

4. An electrical connector according to claim 2 in which each leg of the contact element is provided with an aperture by means of which a conductor introduced into said passage can pass through said contact element into said socket.

5. An electrical connector according to claim 1 in which said end of the contact element which engages with a wall of said passage also forms a closure for a channel in said wall, said channel being adapted to receive a conductor and to guide it to registering apertures in the legs of said contact element.

6. An electrical connector according to claim 1 in which said end of the contact element which engages with a wall of said passage also forms a closure for a channel in said wall, said channel being adapted to receive a conductor and to guide it to registering apertures in the legs of said contact element, a channel in said socket registering with said apertures and adapted to guide said conductor downwardly along the end of the leg of said contact element which is seated in said socket after it has passed through said first mentioned channel and said apertures, the lower end of said channel in said socket registering with a notch in the end of said leg of the contact element seated therein adapted to permit the passage of the conductor from one side of the leg to the other.

CHARLES E. GILBERT. 70
